UNITED STATES PATENT OFFICE.

PHILIP S. MEDART, OF ST. LOUIS, MISSOURI, ASSIGNOR TO FRED MEDART MANUFACTURING COMPANY, OF ST. LOUIS, MISSOURI, A CORPORATION OF MISSOURI.

VAULTING-TROUGH.

1,168,666.

Specification of Letters Patent.

Patented Jan. 18, 1916.

Application filed September 22, 1915. Serial No. 51,961.

To all whom it may concern:

Be it known that I, PHILIP S. MEDART, a citizen of the United States of America, and a resident of the city of St. Louis, in the State of Missouri, have invented certain new and useful Improvements in Vaulting-Troughs, of which the following is a specification.

This invention relates to vaulting appliances employed in athletic exercises, and has for its object to provide a safe and effective fulcrum bearing for the end of a vaulting pole, and with which a resilient impact is provided for the pole end to lessen the jar, and in which all liability to accidental slippage of the pole end is prevented, all as will hereinafter more fully appear.

In the accompanying drawings: Figure 1, is a perspective view illustrating the general arrangement of parts in the preferred form of the present invention. Fig. 2, is a longitudinal section. Fig. 3, is a detached perspective view of the buffer springs and their supporting plate. Fig. 4, is a similar view of the buffer head or plate.

Similar reference numerals indicate like parts in the several views.

Referring to the drawings, 1 designates a curved web or shell constituting the main body or portion of the present open top vaulting trough or bowl, and preferably of an expanded form toward its forward end, and with such end of the open curved form shown to admit an easy entrance of the fulcrum end of the vaulting pole 2. The web or shell 1 is disposed on a downward slope from the above mentioned forward and open end to the hereinafter described rear and closed end of the appliance, with a view to assist in a sliding movement of the fulcrum end of the vaulting pole to and against said rear and closed end.

3 designates a transverse supporting leg or flange at the forward and open end of the shell 1 aforesaid, and preferably formed as an integral part therewith.

4 designates a short transverse supporting leg at the rear end of the shell 1 aforesaid, and preferably formed as an integral part therewith.

5 designates a fixed transverse wall at the rear of the aforesaid shell 1 and preferably formed as an integral part therewith.

6 designates a transverse buffer head or plate hinged at its upper end to the shell 1 aforesaid, and disposed in adjacent spaced relation to the transverse rear wall 4 aforesaid.

7 designates a series of elastic bumpers 60 disposed intermediate of the buffer plate or head 6 and the rear wall 5 aforesaid and adapted to offer a yielding resistance to the movement of said buffer plate or head in actual use. Said elastic bumpers 7 will 65 usually be in the form of short cylinders of rubber or the like.

8 designates a bumper supporting plate interposed between the buffer plate or head 6 and the rear wall 5, and formed with a 70 series of holding orifices for the series of bumpers 7, aforesaid, as shown in Figs. 2 and 3.

9 designates a headed screw or stud extending down from the bottom of the leg 3 75 aforesaid, and adapted for detachable engagement with a fixed floor plate 10, having an elongated and expanded receiving slot 11, as shown. No claim however, is made to such means of connection, and any 80 other and suitable means may be employed instead, without departing from the spirit of the present invention.

Having thus fully described my said invention what I claim as new and desire to 85 secure by Letters Patent, is:—

1. A vaulting trough comprising, an open top member formed with a curved bottom web and having a transverse head at its rear end, substantially as set forth. 90

2. A vaulting trough comprising, an open top member having an inclined bottom and a transverse head at its rear end, substantially as set forth.

3. A vaulting trough comprising an open 95 top member having a transverse head at its rear end, the sides of said member having a flare toward the forward end, substantially as set forth.

4. A vaulting trough comprising an open 100 top member having an inclined bottom and a transverse head at its rear end, the sides of said member having a flare toward the forward end, substantially as set forth.

5. A vaulting trough comprising, an 105 open top member having a transverse buffer plate hinged at its upper end to the rear end of said trough, and an elastic bumper

supporting said buffer plate, substantially as set forth.

6. A vaulting trough comprising, an open top member having a transverse buffer plate hinged at its upper end to the rear end of said trough, and an elastic bumper supporting said buffer plate, the sides of said member having a flare toward the forward end, substantially as set forth.

10 7. A vaulting trough comprising, an open top member having a transverse head at its rear end, a transverse buffer plate hinged at its upper end in spaced relation to and in front of the transverse head aforesaid, and a series of elastic bumpers adapted to provide a bearing for said buffer plate, and a supporting plate formed 25 with a series of holding orifices for said elastic bumpers, substantially as set forth.

15 Signed at St. Louis, Missouri, this 18th day of September, 1915.

PHILIP S. MEDART.

Copies of this patent may be obtained for five cents each, by addressing the "Commissioner of Patents, Washington, D. C."
